UNITED STATES PATENT OFFICE.

ROBERT McDougall, of JACKSONVILLE, FLORIDA.

LOCOMOTIVE-SPRING.

1,321,798.

Specification of Letters Patent. Patented Nov. 11, 1919.

Application filed May 29, 1919. Serial No. 300,784.

To all whom it may concern:

Be it known that I, ROBERT McDougall, citizen of the United States of America, residing at Jacksonville, in the county of 5 Duval and State of Florida, have invented new and useful Improvements in Locomotive-Springs, of which the following is a specification.

The object of the invention is to provide 10 a spring of the leaf type designed especially for use in connection with locomotives and similar heavy vehicles, wherein any desired number of coöperating elements may be employed and may be securely held in proper 15 relative positions without involving the puncturing or perforating of said elements and hence without detracting from the strength thereof or impairing the durability of the same, and to this end the invention 20 consists in a construction, combination and relation of parts hereinafter specifically set forth, it being understood that changes in form, proportion and details may be resorted to within the scope of the claims 25 without departing from the principle involved.

In the drawing:

Figure 1 is a side view of a spring and mounting embodying the invention.

30 Fig. 2 is a transverse section of the same on the plane indicated by the line 2—2 of Fig. 1.

Fig. 3 is a detailed view in perspective of the clamp or chair in which the elements 35 or leaves of the spring are seated and held.

Whereas in the ordinary leaf spring construction it is common to employ one or more bolts disposed at or near the center of the structure for the purpose of maintaining 40 the registration and proper relation of the parts, it is the purpose of the present invention to insure a uniform and permanent relation under all conditions of use and strain without diminishing the transverse rib of the seat in the chair.

45 strength or resistance to flexure, but on the other hand to provide a means for maintaining the desired relation under such conditions as to increase the resistant qualities of the leaves and to graduate the resistant 50 effect in accordance with the relative lengths of the leaves to the end that a maximum efficiency of the structure may be attained.

Obviously when, as in the ordinary practice a nine-leaf spring is employed in connection with a locomotive truck there is a 55 wide difference between the lengths of the

lowermost and uppermost elements, and hence in order to secure the most efficient coöperation it is desirable that there should be a similar graduation of the bearing relations of the elements with reference to the chair or other supporting member, and hence in the present instance there is provided in the chair 10 a base 11 having a transverse rounded bearing rib 12 for reception by a 60 correspondingly rounded offset in the lowermost leaf member 13 and the superposed leaf members are provided with corresponding offsets which nest uniformly and hence increase in extent from the lowermost to the 65 uppermost leaf so that the offsets in all of the several elements of the spring are concentrically disposed. This arrangement involves an offset 14 in the uppermost spring leaf which measures longitudinally of the 70 spring proportionate to the difference in the length of the uppermost leaf as compared with the lowermost leaf, and the offset portions of the several leaves are held in this nested concentric relation by means of 75 transverse retaining pins 16 which connect the arms 17 forming the side walls of the chair, said arms of each wall being diyer- 80 gently related so as to seat said retaining pins or bolts at the points of mergence 85 of the offset 14 with the flat or body portion of the leaf. Obviously the anchoring of the uppermost leaf serves by reason of the intimate nesting of the offsets of the several leaves to effectively lock the latter 90 in their proper relation with the lowermost leaf and hence the latter with the transverse rib of the seat in the chair.

In flexure this arrangement results in a distribution of the strain, and varies the 95 point of maximum bend according to the length of the leaf, so that the maximum efficiency of each element is utilized with a corresponding reduction in the tendency to cause fracture.

100 What is claimed is—

1. A plural leaf spring having leaves of graduated lengths provided at their centers with rounded offsets arranged concentrically in nested relation, in combination with 105 a chair having a rounded bearing rib in engagement with the offset of the leaf of minimum length, and provided with spaced retaining pins in engagement with the leaf of maximum length at the points of mergence 110 of its offset with the body portions of the leaf.

2. A plural leaf spring having its elements provided at their centers with transverse concentrically nested offsets, in combination with a chair having its seat provided with
5 a transverse rounded bearing rib in engagement with the offset of the leaf of minimum length, and having divergent side arms con- nected by transverse retaining pins in engagement with the surface of the leaf of maximum length at the limits of the offset 10 portion of said leaf.

In testimony whereof I affix my signature.

ROBERT McDougall.
